STEREOTYPE PLATE CASTING MACHINE

Application filed April 25, 1932. Serial No. 607,407.

In machines for casting curved stereotype plates it has been customary to cast the plate of sufficient thickness to allow for smooth finishing of the back of the plate in a curved 5 plate shaving machine or a thinning machine. This smooth finishing was necessary because the convex surface of the male member of the casting box is porous, thus causing the back of the cast plate to be more or less rough.

10 The object of my invention is to provide means whereby the necessity of smooth finishing or shaving the back of a curved stereotype plate is eliminated, said means comprising a smooth non-porous facing of heat 15 resisting material, such as clay surfaced paper, for the convex wall of the male member of the casting box; thereby enabling a curved plate to be cast of the desired thickness with a perfectly smooth back.

20 A practical embodiment of my invention is represented in the accompanying drawing, in which

Fig. 1 represents in front elevation so much of a curved stereotype plate casting machine 25 as will give a clear understanding of my invention, portions of the female member, the matrix, the cast plate and the heat resisting facing sheet being broken away to show in full lines the parts back of the same;

30 Fig. 2 represents a vertical section through the casting box, taken in the plane of the line II—II of Fig. 1, looking in the direction of the arrows, and

Fig. 3 represents a horizontal section 35 through the casting box, taken in the plane of the line III—III of Fig. 1, looking in the direction of the arrows.

The casting box comprises the coacting male and female members 1 and 2, which 40 members are brought together for casting the curved stereotype plate and are separated for removing the plate and matrix, in any well known or approved manner.

The matrix 3 is seated as usual along the 45 concave wall of the female member 2 of the casting box before the plate 4 is cast. Also, before the plate is cast the convex wall of the male member 1 of the casting box is covered with a smooth non-porous facing 5 of 50 heat resisting material, between which facing

and the matrix the metal for the plate is poured after the casting box members are closed.

The heat resisting facing is preferably composed of a clay surfaced sheet of paper which 55 is produced by running the sheet of paper through a clay solution and then calendering the sheet to bring it to a uniform thickness.

The heat resisting sheet or facing may be secured around the convex wall of the male 60 member 1 of the casting box by suitable fastening devices, such as bolts 6 arranged along the sides of said male member.

From the above description it will be seen that the stereotype plate is cast between the 65 matrix and the non-porous exposed surface of the heat resisting facing of the male member, thereby ensuring a perfectly smooth back for the plate and eliminating the necessity of subjecting the back of the plate to a 70 shaving or thinning machine.

It is evident that various changes may be resorted to in the construction, form and arrangement of the several parts without departing from the spirit and scope of my invention, and hence I do not wish to be limited to the particular embodiment herein shown and described, but

What I claim is:

1. In a curved stereotype plate casting machine, a male member provided with a smooth non-porous heat resisting facing.

2. In a curved stereotype plate casting machine, a male member provided with a smooth non-porous heat resisting facing composed of a sheet of clay surfaced paper.

3. In a curved stereotype plate casting machine, a male member and a smooth non-porous facing of heat resisting material removably secured over the convex wall of the 90 said member.

4. In a curved stereotype plate casting machine, a male member and a clay surfaced paper sheet removably secured over the convex wall of the said member.

In testimony, that I claim the foregoing as my invention, I have signed my name this 95 22d day of April, 1932.

RICHARD J. GREENWAY. 100
